UNITED STATES PATENT OFFICE.

GEORGE ARTHUR BINNIX, OF WATERLOO, NEBRASKA.

RAILROAD-RAIL JOINT.

No. 906,186.

Specification of Letters Patent.

Patented Dec. 8, 1908.

Application filed January 17, 1908. Serial No. 411,332.

To all whom it may concern:

Be it known that I, GEORGE ARTHUR BINNIX, a citizen of the United States, residing at Waterloo, in the county of Douglas and 5 State of Nebraska, have invented a new and useful Railroad-Rail Joint, of which the following is a specification.

This invention relates to an improvement in railroad rails, more particularly to the 10 ends thereof, the main object being to so fashion the rail ends that the rails may be quickly, easily and rapidly put together, and firmly and rigidly joined without the use of fish plates or other extraneous means except 15 bolts and nuts.

Another object to be derived from the use 20 of joints made by the improved rails is the elimination of butt connections between the rails and substituting lap joints, which latter cause a smoothness of running by passing 25 trains not possible where the rails are butt joined of fastened end to end as are the present form of rail joints.

With these and other objects in view, the 30 invention comprises the various novel features of construction and combination and arrangement of parts, which will be more fully described hereinafter, and set forth more particularly in the appended claims.

35 In the accompanying drawings:—Figure 1 is a cross sectional view through a rail joint showing the improved construction. Fig. 2 is a horizontal section on the line 2—2 of Fig. 1. Fig. 3 is a perspective view of the ends of 40 two rails disconnected, but which when placed together and bolted form an improved rail joint.

Corresponding parts in the several figures 45 are indicated throughout by similar characters of reference.

With the exception of the ends, the rail of the present invention is similar to those in common use, having a base flange 1, a vertical web 2 and a head 3. Each end of the 50 web 2 is thickened for some distance back of the end of the base flange 1, which thickening 4 extends forward of the end of the rail an equal distance to form a tongue 5. The opposite side 6 of the web and the tongue are 55 beveled or inclined to form a scarf joint with the end of another rail similarly formed, the two being firmly united by bolts 7 passing through elongated holes in the tongues and thickened webs and retained in place by nuts 8 as usual.

The ends 9 of the base flanges 1 are cut

square across the rails and abut when brought together, the heads 3, however, being differently formed in order to produce a smooth and substantially unbroken surface 60 for the passing car wheels. This is done by removing a portion of the head of the rail overhanging the beveled side 6 of the web in the same plane as said side and continuous with it. Square shoulders 10 and 11 are 65 formed on opposite sides of the head against which rest similar shoulders on the rail joined thereto. These shoulders are preferably parallel to each other and equally spaced longitudinally on opposite sides of the plane 70 of the base flange end 9. By this construction a rail is produced having a base flange with a square end entirely across the rail fastening, a tongue the height of the web 75 projecting beyond the base flange and integral therewith and a head having two transverse shoulders one beyond and one in rear of the base flange end connected by a beveled surface continuous with the beveled surface of the web and tongue which surface is 80 uninterrupted by projections, depressions or irregularities of any kind.

Rails of this type will be rolled complete, the enlargement and its projecting tongue being formed as described on each end of the 85 rail and on opposite sides of the web, so that whichever end is presented to an end of another rail, there will be no trouble in joining the two. In a joint of this character fish plates are wholly unnecessary and, as the 90 tongues are integral with the rails and the latter are united by a scarf joint, great firmness and strength is produced when the two ends are joined together. Further, by the peculiar joint between the opposing rail 95 heads, the wheels of passing trains will cross said joint without pounding or causing the ends of the rails to vibrate which ordinarily tends to wear them and to impair the track. The self supporting joint of this rail provides a connection which is smooth and rigid 100 and has all the advantages characteristic of a continuous rail, and is a faster track than one constructed in the ordinary manner. A joint of this type is cheaper and is more 105 quickly laid, less material being required to make the joint than where fish plates are used as in the present form of track construction. The bolt holes are elongated to permit expansion or contraction of the rails, and as 110 a further advantage in this form of joint where the tracks are used for carrying an

electric circuit as in a block signal system, the joint itself is sufficient to carry the current without using wire connections between the adjoining rails, as is the present practice. When necessary to insulate two rails, templets of insulating material may be inserted between the beveled or inclined surfaces.

What is claimed is:—

- 10 1. A railroad rail having the base flange at one end for its entire width perpendicular to the length of the rail, its web thickened on one side and projecting beyond said base flange end to form a tongue, the web and web side of said tongue being beveled, said beveled surface extending inwardly from the end of the base flange a distance equal to the projection of the tongue beyond the same.
- 15 2. A railroad rail having the base flange at one end for its entire width perpendicular to the length of the rail, its web thickened on one side and projecting beyond said base flange end to form a tongue, the web and web side of said tongue being beveled, said beveled surface extending inwardly from the end of the base flange a distance equal to the projection of the tongue beyond the same, and transverse shoulders one on each side of the

longitudinal center of the rail head and equally spaced in opposite directions from 30 the plane of the base flange end.

3. A railroad rail having the base flange at one end for its entire width perpendicular to the length of the rail, its web thickened on one side and projecting beyond said base flange to form a tongue and having bolt holes 35 extending therethrough, one side of said web and tongue being inclined at an angle to the line of the rail, the head of said rail having a shoulder on each side of the web in different transverse planes and the plane surface connecting said shoulders continuous with said angular or inclined side, combined with a rail end to form a joint, the inclined faces of each rail being placed in contact with the 40 tongue and thickened portion of one overlapping the other, and bolts for connecting the two rails.

In testimony that I claim the foregoing as my own, I have hereto affixed my signature 50 in the presence of two witnesses.

GEORGE ARTHUR BINNIX.
